UNITED STATES PATENT OFFICE.

FRANK EDWARD HERBERT, OF CHICAGO, ILLINOIS.

MAIL-BAG-HANDLING DEVICE.

No. 923,174.

Specification of Letters Patent.

Patented June 1, 1909.

Application filed February 28, 1909. Serial No. 479,452.

To all whom it may concern:

Be it known that I, FRANK EDWARD HERBERT, a citizen of the United States, residing at Chicago, in the county of Cook and State 5 of Illinois, have invented certain new and useful Improvements in Mail-Bag-Handling Devices, of which the following is a specification.

This invention relates to improvements in 10 mail handling mechanisms and embraces certain improvements designed to provide a more efficient and reliable device for handling mails on a moving train.

The principal object of the invention is the 15 production of mechanism for delivering a mail bag from a moving train and mechanism for receiving the delivered bag adapted to effectively break the momentum of the same and securely hold the bag from injury or loss. 20 With the above and other objects in view the invention embraces certain combinations, constructions and arrangements of parts, clearly described in the following description and in the accompanying drawings 25 in which:

Figure 1 is a side elevation of a stationary receiving mechanism. Fig. 2 is a detailed sectional view of a receiving hopper, or trap forming part of the receiving mechanism. 30 Fig. 3 is a top plan view of the mechanism for receiving a mail bag directly from a moving car and for breaking the momentum thereof. Fig. 4 is a detail top plan view of a portion of the support for the mail bag receiving and buffering mechanism. Fig. 5 is a 35 detail elevation thereof. Fig. 6 is a side elevation of a car mail bag delivering mechanism. Fig. 7 is a detail view of a connecting member therefor. Fig. 8 is a top plan view 40 of the delivering and receiving mechanism in position for delivering and receiving a mail bag. Fig. 9 is a top plan view of a portion of the car delivering mechanism. Fig. 10 is a detail top plan view thereof showing the 45 bag controlling trigger action.

Referring to the accompanying drawings which are prepared for illustrative purposes and accordingly not drawn to scale, numeral 16 denotes a base of concrete having a 50 standard 19 located thereon, and braced against lateral displacement by turnbuckle brace rods 15 which are connected at their lower ends to base blocks 16^a and at their upper ends to apertured lugs 17 formed on a 55 collar 18 mounted on the standard 19. A second collar or sleeve 18^a is mounted for ro-

tation on the collar 18 and is formed with a supporting platform or member L, which extends at right angles therefrom and is braced by a brace 43. The collar 18^a is held in fixed 60 position on the collar 18 by a pin 41, which is adapted to be inserted in registering apertures formed in the collars 18 and 18^a, and which is flexibly connected to the brace 43 by a chain 42. An upstanding supporting 65 guide member M is located on the end of the support L nearest the standard 19, and a second upstanding guide member M^a is located on the opposite end thereof.

A series of guide rods E and E' extend 70 slidably through the supports M and M^a and are connected at their outer ends to a buffer plate D which is provided with a reinforced head piece and with a cross piece D' which is connected to a second set of guide rods F 75 which extend slidably through apertured lugs formed in the collar 18^a and which are provided with expansion springs F'.

A frame work comprising end members B² and B³ and side members B' is mounted 80 on the supports M and M^a, and a pair of gripping arms C are pivoted at their rear ends to the end member B³. Each of the gripping arms is formed with curved portions C^a having upstanding flanges C^b and depending 85 legs C' formed thereon. The gripping arms C are pivotally connected by links K intermediate of their ends, and the links K are pivotally connected to a link J having pivotal connection with a bar E² mounted on 90 the rods E and which is connected by compression springs H with the cross piece I of the support M. A plate B is mounted on the frame work B', B² and B³ and is provided with a trip spring G connected thereto by a 95 strap G'. A trap box or hopper 44 having trap doors 46 hinged at 45 thereto and controlled by springs 47 is located directly beneath the arms C, so as to receive mail therefrom. 100

A mail bag supporting arm Q having apertured lugs Q' is pivotally connected by a bolt q thereby to a connecting member N having bolts for holding the same to a car, and a spring P for holding the arm normally 105 outward from the car; said spring being formed with a penetrating end p which slidably moves in an opening 40 formed in said member N. The outer end of the arm Q carries a pair of spring closed jaws S which 110 are pivoted to bars R attached to the arm Q and are connected together by a spring 29.

The arm Q carries a trigger block T adapted to be held between the jaws S and pivotally supported on said arm; said trigger block being arranged to support a mail bag when 5 the free end thereof is held between the jaws S. A swinging rod 23 is pivoted to the arm Q by means of blocks 24, having pivot 26 passed therethrough and connected to apertured lugs 25. The rod 23 is provided on 10 its outer end with a bag engaging piece 27 having rods 39 connected thereto, whereby a mail bag suspended by the trigger block T is steadied on the arm Q. A strap 22 is located on the rod 23 and a spring 21 is connected with said strap and with the arm Q 15 for holding the same in a vertical position on said arm.

In operation a mail bag is suspended on 20 the trigger block T and said block is locked between the spring controlled jaws S. As the arm Q is moved into engagement with the receiving mechanism, the trip spring G of the plate B will force the trigger block T from the jaws S and the mail bag will be 25 simultaneously forced against the buffer plate D so that the links K connected with the gripping arms C will be actuated by the yielding of the buffer plate and said arms will be caused to temporarily grip the mail 30 bag. When the momentum of the mail bag has been absorbed and expended, the gripping arms C will automatically open by reason of the tension of the springs F and H, and the mail bag will fall onto the trap doors 35 of the receiving box or hopper 44, which doors tend to break the fall of the bag, and are adapted to automatically close when the bag has entered the box. The various parts are so arranged that efficiency is attained 40 and the danger of injured mail is largely eliminated.

Having thus described my invention, what I claim to be new and desire to secure by Letters Patent is:

45 1. In a device of the class described, a support, buffing mechanism arranged thereon, gripping arms pivoted thereon, springs for holding the gripping arms normally apart, means for temporarily closing said gripping 50 arms, and a trap box for receiving mail from the gripping arms.

55 2. In a device of the class described, a yielding mail bag buffer mechanism, mail bag gripping arms co-acting with the buffer mechanism, means for holding the arms normally apart and means for temporarily closing said gripping arms.

3. In a device of the class described, a support, buffing mechanism arranged there-

on, gripping arms pivoted on the support, 60 and a trigger mechanism for delivering mail to the gripping arms and the buffing mechanism in combination with a bag holding arm pivotally secured to a car, said arm having spring actuated jaws secured thereto. 65

4. In a device of the character described, a support, buffing mechanism arranged yielding thereon, a pair of co-acting gripping arms arranged on the support, a receiving trap box located beneath the gripping arms, 70 in combination with a swinging car supported arm, and bag supporting trigger mechanism carried by the arm for delivering mail bags to the gripping arms and receiving box. 75

5. In a device of the class described, a standard, a yielding buffer supported thereon, a pair of pivotally united gripping arms, means for connecting the gripping arms to the buffer mechanism, means for holding the 80 gripping arms normally apart and means for temporarily closing said gripping arms.

6. In a device of the class described, a standard, a supporting frame arranged for rotation thereon, a spring controlled yielding 85 buffer supported on the frame, a pair of gripping arms pivotally supported on the frame, and means for connecting the gripping arms to the buffer in combination with a bag holding arm pivotally secured to a car, 90 said bag holding arm having spring actuated jaws secured thereto.

7. In a device of the class described, a bag holding arm pivotally secured to a car, 95 spring closed jaws arranged on the bag holding arm, a bag supporting trigger block pivoted at one end to the holding arm and adapted to have its free end engaged by the jaws, and stationary receiving means for actuating the jaws and releasing the bag 100 from said trigger block.

8. In a device of the character described, a bag holding arm pivotally secured to a car, spring closed jaws arranged on the holding arm, a bag supporting trigger block pivotally secured at one end to the holding arm and engaged at its free end by the jaws, a stationary trip for releasing the trigger block from the jaws, a buffer mechanism for absorbing the momentum of a moving bag, 110 and co-acting spring controlled gripping jaws for temporarily holding a delivered bag.

In testimony whereof I affix my signature, in presence of two witnesses.

FRANK EDWARD HERBERT.
